Primary Examiner — Michael C Stout*Assistant Examiner* — Eric Eldone Tormanen(74) *Attorney, Agent, or Firm* — Vladimir Postnikov(57) **CLAIM**

The ornamental design for a test strip, as shown and described.

DESCRIPTION

FIG. 1 is a front-right-top perspective view of a test strip showing our new design;

FIG. 2 is a front elevation view thereof;

FIG. 3 is a rear elevation view thereof;

FIG. 4 is a right side elevation view thereof, the left side elevation view being a mirror image of FIG. 4; and, FIG. 5 is a top plan view thereof; the bottom plan view being a mirror image of FIG. 5.

The equal length broken lines depict portions of the test strip that form no part of the claimed design.

The dash-dot broken lines represents a symbolic break within the test strip. The appearance of any portion of the test strip between the symbolic break forms no part of the claimed design.
